Design No. 12,014, dated November 2, 1880.

UNITED STATES PATENT OFFICE.

EDUARD LEISSNER, OF NEW YORK, N. Y., ASSIGNOR TO LEISSNER & LOUIS,
OF SAME PLACE.

DESIGN FOR WALL-PAPER.

SPECIFICATION forming part of Design No. 12,014, dated November 2, 1880.

Application filed July 31, 1880. Term of patent 3½ years.

To all whom it may concern:

Be it known that I, EDUARD LEISSNER, of the city of New York, county and State of New York, have invented a new and original 5 Design for Wall-Paper, of which the following is a specification.

This invention relates to a new and original design for wall-paper and similar fabrics.

It consists in the novel grouping and configuration of figures hereinafter more fully described.

The accompanying photograph illustrates a face view of wall-paper having my new design.

15 The background is formed of a series of circular figures, A A A A. Each of these circular figures A A is composed of a series of concentric circles, and the size of each figure depends on the diameter of its outermost circle.

20 In the center of the innermost circle of each figure A is to be a star-shaped figure. (Dimly perceptible in the photograph.) These circular figures A A A are laid so that their edges lap over one another successively, forming

25 what appears to be a solid background without interstices. Upon this background appear figures of various shapes. Rosette-like figures

B appear always in connection with and overlapping other rosette-like figures, E. The design contains four pairs of such double rosettes 30 B E—two pairs near the upper left-hand corner and two pairs near the lower right-hand corner.

Two large flowers, C' C', apparently in full bloom, appear, one near the upper right-hand 35 corner and the other toward the left-hand lower corner of the design. Two similar smaller flowers, C² C², also appear, one in the left-hand lower corner, the other upon the right of the design. A flower-like figure, G, stands 40 nearly in the center of the design.

In the spaces between the figures B D E G are found leaf like figures D D D D, filling the greater part of those spaces. These leaves show distinctly their branching fibers. 45

I claim—

The design for wall-paper, consisting of the background composed of figures A A A, having upon it, in the foreground, the figures B E C' C² D G, substantially as shown.

EDUARD LEISSNER.
